UNITED STATES PATENT OFFICE

THOMAS C. SHEEHAN, OF UPPER MONTCLAIR, NEW JERSEY, ASSIGNOR TO DURHAM DUPLEX RAZOR COMPANY, A CORPORATION OF NEW YORK

HEAT TREATING RAZOR BLADE STRIPS

Application filed July 12, 1929. Serial No. 377,695.

This invention relates to heat treating metal strips, particularly thin steel strips such as those from which safety razor blades are formed. The present invention is particularly applicable, though not limited to, the production of safety razor blades which are very hard at the edges, and consequently hold their edge well, and yet soft at the center so that they are not liable to break when bent to fit a curved holder, as are blades which are made hard throughout.

It is one of the principal objects of the invention to provide a heat treating method and apparatus applicable to the rapid and economical production of such blades. To this end it is an object of the invention to provide for continuously heat treating a traveling thin steel strip prior to cutting to blade lengths, to uniformly temper such blades at low cost. Another object is to provide a method and means for drawing the temper from a selected portion of a tempered strip so that articles cut therefrom will be hard where hardness is desirable and relatively soft where brittleness is objectionable. Other objects are to dispense with troublesome fluid baths, to provide efficient cooling or quenching means operating through surface contact with the strip, and in such means to distribute the wear and heating effect of the strip over a wide area.

With these and other objects not specifically mentioned in view, the invention consists in certain constructions and combinations which will be hereinafter fully described and then more particularly pointed out in the claims.

In the accompanying drawings which form a part of this specification and in which like characters of reference indicate the same or like parts:

Fig. 1 is a side elevation of a machine constructed in accordance with the invention with a portion of the furnace broken away;

Fig. 2 is a rear elevation of the machine shown in Fig. 1;

Fig. 3 is a plan view of the machine shown in Fig. 1;

Fig. 4 is an enlarged detail plan view, part-

ly broken away, of a portion of the machine shown in Fig. 1;

Fig. 5 is a vertical longitudinal section taken on the line 5—5 of Fig. 4;

Fig. 6 is an enlarged detail plan view of the furnace shown in Fig. 1 with the top plates removed;

Fig. 7 is a vertical section of the furnace taken on the line 7—7 of Fig. 8;

Fig. 8 is a cross section of the furnace taken on the line 8—8 of Fig. 6;

Fig. 9 is a detail view of the exit end of the furnace taken on the line 9—9 in Fig. 5.

Fig. 10 is a detail perspective view of one of the guides shown in Fig. 1;

Fig. 11 is an enlarged detail elevation, partly in section, of the cooling device shown in Fig. 1;

Fig. 12 is a plan view of the cooling device;

Fig. 13 is an end view of the device shown in Fig. 11;

Fig. 14 is a vertical cross section through the temper drawing mechanism shown in Fig. 1;

Fig. 15 is a plan view of the exit end of the temper drawing mechanism taken on the line 15—15 in Fig. 5;

Fig. 16 is a detail plan view of the razor blade strip;

Fig. 17 is a diagrammatic cross section of the razor blade strip shown in Fig. 16; and

Fig. 18 is an enlarged detail view of a portion of the mechanism shown in Fig. 14.

The apparatus used in carrying the invention into effect comprises mechanism for feeding a metal strip, means for tempering the strip as it is fed, and devices operating on the strip fed from the tempering means to draw the temper from a selected portion thereof in order to produce a strip which is hard where hardness is desirable and yet relatively soft where brittleness is objectionable. In the best constructions, the tempering means includes a furnace designed to uniformly heat the strip and a combined guide and flame baffle for said strip extending through said furnace. In the best form, the tempering means includes a moving cooling surface contacting said strip. Preferably, a plurality of reciprocating cooling surfaces are provided

engaging opposite sides of the strip. In the best constructions also, said devices include a hot surface contacting a selected portion of the strip. The method utilized in carrying out the invention consists in imparting feeding movement to the strip, then heating and rapidly cooling the strip to temper the same and passing a selected portion only of the cooled strip into contact with a hot surface to draw the temper of that portion of the strip, to make the strip relatively soft and flexible at that part. The above means and method may be widely varied in practice within the scope of the claims, for the particular structure and method selected to illustrate the invention is but one of many possible concrete embodiments of the same. The invention, therefore, is not to be restricted to the precise details shown and described.

Referring to the drawings, the device selected to illustrate the invention consists generally of a furnace F through which the strip is passed from left to right, a cooling or quenching device C into which the heated strip passes and in which it is rapidly cooled or chilled to give the strip a hard temper, a temper drawing device D into which the tempered and cooled strip in which a selected portion thereof is reheated to draw the temper of that portion of the strip, and strip feeding means R which serves to continuously draw the strip through the preceding mechanism.

The strip S from which, in the present embodiment, razor blades are to be subsequently formed, is fed up a guideway 19 (Fig. 1.) and into the furnace F which consists of a trough shaped outer casing 20 carried on a table 22 constituting the base for several parts of the machine, having a fire-brick lining 25, and closed at the top with a refractory top plate 24. A series of projecting fire bricks 26 serve to support a pair of oppositely disposed longitudinal guides 28 extending into and through the furnace and provided with opposed pairs of bosses 30 and 31 and grooves 32 receiving the edges of the strip. The bosses which are arranged at intervals along the length of the guides, serve to support and guide the central portion of the strip, while permitting free access of the heat of the furnace, to prevent curling or bending thereof, while the grooves at the edges support the edge portions of the strip.

In order to uniformly heat the strip S as it is fed through the furnace, a series of gas nozzles 35 on either side of the furnace are arranged at equal distances from each other lengthwise of the furnace and are also equally spaced from the sides of the guides 28 remote from the strip. Thus the guides will serve to baffle the flame, in order to prevent burning of the thin strip, by the direct action from the gas flames on the strip. The strip then passes out of the furnace at the exit end, closed

by an apertured plate of refractory material 36.

To rapidly cool or quench the heated strip in order to temper the strip to hardness (in the present instance to the hardness desirable for the cutting edges of razor blades), the strip is passed between reciprocating cooling surfaces 40 and 41 of the temper drawing device C. These surfaces are formed on a pair of tanks 42 and 43 and are mounted for reciprocation across the faces of the traveling strip on the transverse guide rails 44 and 45 by means of bored lugs 47 and 48 respectively.

To regulate the pressure under which these cooling surfaces engage the opposite faces of the strip, the guide rails 44 are supported for movement toward and away from the guide rails 45 by bosses 50 at either end of these rails, carried by slides 51 in guides 52 and held against lateral movement by cap screws 53 in vertical slots 54 of the slides 51. These cap screws are secured in a pair of brackets 55 which constitute the main support for the cooling device C. Thus the weight of the upper cooling tank and supporting rails rest on the face of the strip pressing it against the strip of the lower cooling tank. This pressure is accurately regulated by means of screws 56 adjustable in lugs 57 on brackets 55 and supporting at their upper ends springs 58 bearing on the lower side of the slide 51. Thus movement of the screw upward would decrease the pressure of the cooling surface on the strip, and downward would increase said pressure.

For inspection and in emergencies, the cooling surfaces are quickly spread apart by means of the hand lever 61 secured to rock shaft 62 on which is fixed a pair of cranks 63 connected by links 64 with cross bars 65 connecting the guide rails at each end. The reciprocating motion of the tanks 42 and 43 relative to the strip is produced by a walking beam 66 connected at one end by link 67 to upper tank 42 and at the other end by link 68 to the lower tank 43 and pivoted at its center with one of the brackets 55 by lugs 69 and the pivot pin 70 extending therethrough. The walking beam 66 is oscillated by a link 71 connected to its lower end and operated by a crank 72 on a shaft 73 of reducing gear 74 driven through a chain drive 75 from the main shaft 76 of the machine.

The tanks 42 and 43 which are provided with a series of baffles 80 and 81 to distribute the flow of cooling liquid therein and thus uniformly cool the surfaces engaging the strip, are supplied with cooling liquid, ordinarily brine, through flexible pipes 82 connected to suitable supply and discharge pipes 83 and 84. Thus the strip as it passes through the cooling device C is rubbed across its faces at a regulated pressure by ever changing uniformly cooled surfaces, whereby the wear and

heated effect caused by the strip is evenly distributed over the cooling surfaces.

The cooled and tempered strip then passes into the temper drawing device D through the apertured insulating block 90. This device consists of a heated metal block or anvil 91 having a narrow rib 92 extending longitudinally of the strip and having an upper horizontal face 93 engaging a selected portion of the strip from which it is desired to draw the temper, which, as illustrated, is the central portion of the strip which will afterwards form the central bent portion of razor blades formed from the strip. This surface 15 is indirectly heated by means of gas nozzles 94 directed upwardly from either side of the block 91 against its underside or bottom surface. The heat is confined to the block by suitable furnace construction, such as an outer 20 casing 96, a refractory lining 97, and a refractory perforated top plate 98. The central portion of the strip is held against the surface 93, and upward curling of the strip (to which such a strip has a tendency when 25 heated on one side) prevented by a series of rollers 100 mounted at intervals along the upper face of the strip by means of pins 101 and a bar 102 secured to an arm 103 pivoted on an axis 104 parallel to the strip in a bracket 30 105. The weight of the bar 102 and arm 103 is made such that the rollers 100 act on the strip with a predetermined pressure found suitable for this purpose. The strip as it passes from between the surface 93 and 35 the rollers 100 will be very hard at the edges but soft, and therefore easily bendable without danger of breaking at the center.

The strip now passes between the friction rollers 110 and 111 of the strip feeding device 40 R which, in the construction shown, is continuously driven to draw the strip through the several devices already described. The upper roller 110 is pivoted on a head block 111a which is movable up and down by a screw 45 112 so as to adjust the pressure of the rollers. The shaft 115 of the lower roller is driven from the main shaft 76 of the machine, by means of a coupling 116, a gear 117 on the roller shaft 115 engages a gear 118 on the 50 shaft 119 of the upper roller 110. The roller shafts 115 and 119 are supported in a pair of brackets 120 mounted on the table 22. The main shaft 76 of the machine is suitably driven through the reduction gearing 121 and pulley 122 and belt 123 from a motor 124.

What is claimed is:

1. The combination with mechanism for feeding a metal strip, of means for tempering the strip as it is fed, and devices operating on the strip fed from the tempering means to draw the temper from the mid portion thereof only.
2. The combination with mechanism for feeding a metal strip, of means for tempering the strip as it is fed, and devices operating on the strip fed from the tempering means to draw the temper from the mid portion thereof only.
3. The combination with mechanism for feeding a metal strip, of means for tempering the strip as it is fed, and devices operating on the strip fed from the tempering means to draw the temper from the mid portion thereof only, said mechanism operating to feed the metal strip continuously.
4. The combination with mechanism for feeding a metal strip, of means for tempering the strip as it is fed, and devices operating on the strip fed from the tempering means to draw the temper from the mid portion thereof only, said tempering means including an elongated furnace having a series of gas nozzles on either side of said strip, said nozzles being arranged lengthwise of said strip and equally spaced from said strip and each other to uniformly heat the strip.
5. The combination with mechanism for feeding a metal strip, of means for tempering the strip as it is fed, and devices operating on the strip fed from the tempering means to draw the temper from the mid portion thereof only, said tempering means including a furnace and a guide for said strip extending through said furnace.
6. The combination with mechanism for feeding a metal strip, of means for tempering the strip as it is fed, and devices operating on the strip fed from the tempering means to draw the temper from the mid portion thereof only, said tempering means including a furnace and a combined guide and flame baffle for said strip extending through said furnace.
7. The combination with mechanism for feeding a metal strip, of means for tempering the strip as it is fed, and devices operating on the strip fed from the tempering means to draw the temper from the mid portion thereof only, said tempering means including a cooling surface contacting the strip.
8. The combination with mechanism for feeding a metal strip, of means for tempering the strip as it is fed, and devices operating on the strip fed from the tempering means to draw the temper from the strip, said tempering means including horizontally reciprocating cooling surfaces engaging opposite sides of said strip.
9. The combination with mechanism for feeding a metal strip, of means for tempering the strip as it is fed, and devices operating on the strip fed from the tempering means to draw the temper from the strip, said tempering means including a horizontally moving tank for cooling liquid having an external surface engaging said strip.

10. The combination with mechanism for feeding a metal strip, of means for tempering the strip as it is fed, and devices operating on the strip fed from the tempering means to draw the temper from the strip, said tempering means including a tank for cooling liquid having a surface engaging said strip and means for reciprocating said tank horizontally to cause relative movement 10 of said surface and said strip.
11. The combination with mechanism for feeding a metal strip, of means for tempering the strip as it is fed, and devices operating on the strip fed from the tempering means 15 to draw the temper from the strip, said tempering means including cooling surfaces between which the strip is fed, slides connected to one of said cooling surfaces, springs supporting said slides, and means for adjusting 20 the pressure of said springs for regulating the pressure with which said cooling surfaces engage the strip.
12. The combination with mechanism for feeding a metal strip, of means for tempering the strip as it is fed, and devices operating on the strip fed from the tempering means to draw the temper from the mid portion thereof only, said devices including a hot surface contacting said portion of the strip. 25
13. The combination with mechanism for feeding a metal strip, of means for tempering the strip as it is fed, and devices operating on the strip fed from the tempering means to draw the temper from the mid portion thereof only, said devices including a metal 30 block having a surface engaging the selected portion of the strip and means for indirectly heating said surface by heating another portion of said block.
14. The combination with mechanism for feeding a metal strip, of means for tempering the strip as it is fed, and devices operating on the strip fed from the tempering means to draw the temper from the mid portion 35 thereof only, said devices including a hot surface on which said strip rests and a series of rollers pressing on the other side of said strip.
15. Means for rapidly and uniformly cooling a traveling metal strip comprising oppositely disposed cooling surfaces engaging opposite sides of said strip, and means for imparting to said surfaces movement transverse to that of said strip. 40
16. Means for rapidly cooling a traveling strip comprising a tank for cooling liquid having a surface engaging a face of said strip, and means for moving said tank transversely 45 relative to said strip.
17. Means for rapidly cooling a traveling strip comprising a tank for cooling liquid having a surface engaging a face of said strip, and means for moving said tank transversely 50 relative to said strip, said cooling tank hav-
- ing baffles for uniformly distributing the cooling liquid therein.
18. The method of heat treating thin steel strips which consists in imparting feeding movement to the strip, then heating and rapidly cooling the strip to temper the same and passing the mid portion only of the cooled strip into contact with a hot surface to draw the temper of that portion of the strip. 55
19. The method of heat treating thin steel strips which consists in imparting feeding movement to the strip, then heating and rapidly cooling the strip to temper the same and passing the mid portion only of the cooled strip into contact with a hot surface to draw the temper of that portion of the strip, said cooling step consisting in rubbing a cold surface across the face of the strip. 60
- In testimony whereof, I have signed my name to this specification. 65
